[57] CLAIM

The ornamental design for a tape folder, substantially as shown and described.

DESCRIPTION

FIG. 1 is a side elevational view of the tape folder showing our new design;

FIG. 2 is a top plan view thereof;

FIG. 3 is a bottom plan view thereof;

FIG. 4 is an end elevational view taken from the right of FIG. 1;

FIG. 5 is an end elevational view taken from the left of FIG. 1;

FIG. 6 is a sectional view taken in the direction of the arrows on line 6—6 of FIG. 1;

FIG. 7 is an elevation view of the interior taken in the direction of the arrows on line 7—7 of FIG. 2; and

FIG. 8 is an exploded perspective view thereof.

FIG. 1**FIG. 2****FIG. 3****FIG. 4****FIG. 5****FIG. 6****FIG. 7**FIG. 8
